UNITED STATES PATENT OFFICE.

GEORGE A. SEIB, OF SYRACUSE, NEW YORK, ASSIGNOR TO THE MONARCH TYPEWRITER COMPANY, OF SYRACUSE, NEW YORK, A CORPORATION OF NEW YORK.

TYPE-WRITING MACHINE.

No. 904,155.

Specification of Letters Patent.

Patented Nov. 17, 1908.

Application filed May 8, 1906. Serial No. 315,850.

To all whom it may concern:

Be it known that I, GEORGE A. SEIB, a citizen of the United States, and resident of Syracuse, in the county of Onondaga and State of New York, have invented certain new and useful Improvements in Type-Writing Machines, of which the following is a specification.

My invention relates more especially to the carriage feeding mechanism of typewriting machines. In machines of this character in which the letter space feeding mechanism for the carriage or traveling element is separably or detachably connected therewith, as where such connection includes a feed rack and a feed pinion, said rack and pinion normally meshing but being adapted to be separated to release or free the carriage, it sometimes happens, as for example when the carriage is being back spaced or moved in reverse direction a letter space distance at a time, that said carriage is moved so quickly that its momentum overcomes the tension of the spring or springs which are usually employed to maintain the carriage operatively connected with its letter space feeding mechanism. Consequently the parts separate or jump out of engagement and thus allow the carriage to move more than the desired distance.

One object of the invention is to prevent the separation of the carriage from its step-by-step feeding mechanism when such separation is not desired. In the present instance this object is carried out by providing a feed rack which is pivoted on the carriage with a locking latch which locks the rack normally in engagement with a feed pinion which is one of the elements of the step-by-step or letter space feeding mechanism. Said latch is adapted to be automatically unlocked when it is desired to release the carriage from its step-by-step feeding mechanism, as for example, when the carriage release key is operated or when the tabulating devices are operated.

Another object of the invention is to provide improved means for back spacing the carriage.

Another object is to provide an improved means for adjusting the carriage feed rack relatively to the carriage.

Other objects will subsequently appear.

To the above and other ends, the inven-

tion consists in the features of construction, 55 combinations of devices and arrangements of parts to be hereinafter fully described and particularly pointed out in the claims.

One form of the invention is illustrated in the accompanying drawings, wherein 60

Figure 1 is a vertical front to rear sectional view of so much of a typewriting machine as is necessary to a clear understanding of the invention. Fig. 2 is a rear elevation of the machine, parts being broken 65 away and parts being omitted. Fig. 3 is a fragmentary full sized top plan view partly in section of part of the carriage and carriage feeding mechanism, showing my invention applied thereto. Fig. 4 is a rear elevation of part of the back spacing mechanism, the top plate of the machine being shown in section. Fig. 5 is a view corresponding to Fig. 4 but showing some of the parts in different relations from those in 70 which they appear in said Fig. 4. Fig. 6 is an enlarged transverse central sectional view of the escapement wheel, back spacing wheel and their associate devices. Fig. 7 is a sectional view taken on a plane represented 75 by the line $x-x$ in Fig. 6 and looking in the direction of the arrows at said line. Fig. 8 is an enlarged fragmentary rear view showing part of the escapement wheel and the normally engaged escapement dog, which 80 dog carries a back stop, said back stop being shown in operative position. Fig. 9 is a full-sized fragmentary rear elevation showing part of the feed rack, the feed rack lock being shown just after it has been 85 moved to inoperative position. In this figure the feed pinion shaft and its bearing are shown in section for the sake of clearness. Fig. 10 is a view corresponding to Fig. 9 but showing some of the parts in different relations from those in which they appear in 90 said Fig. 9. Fig. 11 is an enlarged fragmentary transverse sectional view showing the feed rack, the feed rack lock and the associate parts. Fig. 12 is a view corresponding 95 to Fig. 11 but showing a modified form of some of the parts.

I have shown my invention as applied to a machine generally resembling that commercially known as the Monarch typewriter, 100 but it is to be understood that the nature of the invention is such that it may be readily adapted to other forms of writing machines.

Referring now more especially to Figs. 1 and 2 of the drawings, the main frame of the machine is shown as comprising a base 1, corner posts 2 and a top plate 3. Key levers 4 are fulcrumed on a fulcrum plate 5 mounted in the rear of the base, each key lever being provided with a restoring spring 6 and having pivoted to it at 7 a sub-lever 8. Each sub-lever is slotted at 9 to coöperate with a fixed abutment 10 and is connected at its upper end by a link 11 with a type bar 12 pivotally connected with a type bar hanger 13, said hanger being secured by a screw 14 to a vertically disposed segmental type bar support 15. For the purposes of this invention it is immaterial whether or not said segmental support is shiftable, but preferably it is provided with suitable shifting mechanism. The type bar hangers are radially arranged in segments of circles and the type bars 12 are normally supported at their free ends on a type rest 16 and are adapted to coöperate with the front face of a rotary platen 17, said platen being journaled in side bars 18 projecting forwardly from opposite ends of a rear bar 19, said side bars and rear bar constituting a platen carrier or carriage. The top and bottom faces of the rear bar are grooved longitudinally to coöperate with anti-friction balls 20, the balls also coöoperating with stationary grooved guide rails 21 which are secured by screws 22 to curved standards or brackets 23 rising from the top plate. Bearing lugs 24 project inwardly from the rear of each side arm of the platen carriage, as best shown in Fig. 3. Said lugs are formed with bearing openings which receive bearing sleeves 25, presently to be more fully described.

Each sleeve receives and pivotally supports at its inner end a pivot pin 26 provided with a flange 27. Each flange is adapted to abut against the inner end of the associate sleeve 25 at one side, said sleeve serving thereby to limit the axial inward movement of the pivot pin 26. At its other side each flange 27 coöperates with a rack supporting arm 28. As will be understood from a consideration of Fig. 3, the forward end of each arm 28 is perforated and is mounted on the inner end of the pivot pin 26, which end is thereafter spread or up-set forcing the arm 28 against the associate collar 27, the construction being such that the arm is thereafter maintained in a fixed relation with its associate pivot pin 26. The rear ends of the arms 28 are bent inwardly towards each other and the bent portions 29 having secured to them by screws 30 a carriage feed rack 31. The feed rack, as shown in Fig. 1, normally meshes with a feed pinion 32 which is fixed at the forward end of a shaft 33, said shaft being supported in a bearing formed in a bracket 34 fixed to the top plate.

A circular feed rack or escapement wheel 35 is loosely mounted on the rear end portion of the shaft 33, said escapement wheel, as shown in Fig. 6, having a forwardly projecting hub 36 which surrounds the shaft 33 and serves as a bearing therefor, and which in turn has a bearing in the supporting bracket 34. The escapement wheel 35 is provided with peripheral teeth 37 and has suitably secured to its rear face, as by rivets 38, a small ratchet wheel 39 (Figs. 6 and 7). A housing or cover 40 surrounds the ratchet wheel 39 and is provided with a central boss or hub 41 which receives set screws 42, the ends of said set screws abutting against the rear end portion of the shaft 33 and serving to maintain the housing 40 in a fixed relation with said shaft. A pawl 43 is pivoted at 44 to said housing and is pressed into engagement with the ratchet wheel 39 by a leaf spring 45, said leaf spring being secured by a rivet 46 to the inner wall of the housing 40. The construction is such that when the shaft is turned in letter space direction, indicated by the arrow in Fig. 7, the escapement wheel 35 is caused to turn with said shaft by reason of the engagement of the pawl 43 with the ratchet wheel 39, but when the carriage is retracted and the shaft is turned in the opposite direction, the pawl 43 is adapted to slide over the teeth of the ratchet wheel 39 and a relative turning movement between the shaft 33 and the escapement wheel 35 may be effected.

Fixedly secured to the rear end portion of the shaft 33 is a toothed back space wheel. In the present instance I have preferred to provide such a ratchet wheel by forming the periphery of the housing 40 with teeth 47. By this construction the housing 40 not only serves its original purpose but also performs the functions of a back space wheel which is coöperative with other back spacing devices presently to be described to effect a step-by-step movement of the carriage backwardly or in an opposite direction to the step-by-step feeding movement thereof. Normally engaging one or another of the teeth 37 of the escapement wheel 35 is a dog 48 pivotally mounted at 49 near the top of the upright arm 50 of a vibratory dog carrier or rocker 51, said dog carrier, as clearly shown in Fig. 2, being pivoted at its ends on screw pivots 52 which are supported in a bracket 53 depending from the top plate. The dog 48 is best shown in Fig. 8. Said dog is provided with an individual dog spring 54 which constantly tends to press said dog away from the face of the rocker arm 50 or towards the right in Fig. 8. A back stop 55 is preferably mounted on the dog 48 and is adapted to coöperate with the backs of the teeth 37 of the escapement wheel to prevent excessive reverse turning movement of said escapement wheel, said back stop operating for this

purpose in a manner fully set forth in the patent to Carl Gabrielson, No. 717,837, dated January 6th, 1903.

The operative position of the back stop is shown in Fig. 8, but it will be understood that normally said stop is maintained out of the path of the teeth of the escapement wheel, as shown in Fig. 2. A second dog 56 is mounted at the top of the dog rocker and is adapted to coöperate with the escapement wheel, said dog in the present instance being shown secured in a fixed relation with the rocker arm 50. A horizontally disposed arm 57 projects forwardly from the dog rocker 51 and is connected by a link 58 to an arm 59 of a universal bar frame pivoted at 60 at the sides of the base 1 and carrying a universal bar 61. Said universal bar extends from side to side of the machine beneath the series of character key levers 4 and the space levers (not shown). When any key lever 4 is actuated the associate type bar is caused to coöperate with the platen in a known manner and the dogs 48 and 56 coöperate with the escapement wheel 35 to permit the carriage to be drawn a letter space distance towards the right under the influence of a carriage spring drum 62 pivoted at 63 to the bracket 53 and connected by a band or strap 64 with a pin 65 depending from the rear bar 19 of the platen carrier or carriage.

Sometimes it is desirable to move the carriage a letter space distance at a time in reverse direction, that is, in a direction opposite to that of the letter space feed movement. To accomplish this result I provide mechanism now to be described.

Referring more especially to Figs. 1, 2, 4 and 5, 66 represents a pawl pivoted at 67 to the left-hand arm (considered from the front of the machine) of a horizontally disposed lever 68 of the first order, said lever being pivoted at 69 to a lug 70 depending from the top plate 3. The pawl 66 is provided with a tail portion 71, said tail portion being normally maintained in engagement with a fixed stop by a C-shaped spring 72, said spring being secured to the lever 68 at one end by a screw 72^a and bearing at its free end against the tail of the pawl. In the present instance a part of the under side of the top plate serves as a stop with which the tail of the pawl is normally maintained in engagement by the spring 72, as shown in Fig. 2. From an inspection of this figure it will be noted that normally the pawl 66 is disengaged from the teeth 47 of the back space wheel or housing 40. The left-hand arm of the pawl supporting and actuating lever 68 is provided with a stop portion 73 which is normally maintained in contact with a fixed stop, a part of the under side of the top plate serving in the present instance as such fixed stop. The right hand arm of the lever 68 (when viewed from the front

of the machine) is connected by a vertically disposed link 74 with a key lever 75 pivoted at 75^a intermediate its ends (Fig. 1) to a lug 76 (Fig. 2) projecting laterally inward from the right-hand side of the base. Said key lever is provided with a key button or cap 77 and with a restoring spring 78 which is coiled around the supporting lug 76 and serves to restore the key lever 75 to normal position and to normally maintain the stop portion 73 of the lever 68 in contact with the top plate as illustrated in Fig. 2.

Referring now to the operation of the back spacing mechanism, when the back space key 77 is actuated, the rear arm of the lever 75 will be elevated, raising the link 74 and the right-hand arm of the lever 68 and lowering the left-hand arm of said lever about the pivot 69. During the first part of the downward movement of the left-hand lever arm 85 the tail 71 of the back space pawl will be maintained in contact with the top plate by the spring 72, the result being that the pawl will be turned on its pivot until said pawl engages with the teeth 47 of the back space 90 wheel 40. Fig. 4 illustrates the position of the pawl 66 at this stage.

When the pawl 66 has been turned on its pivot 67 so as to fully engage with the back space wheel 40 further inward pivotal movement of the pawl will be prevented and as the downward movement of the left-hand lever arm of the lever 68 is continued the pawl as a whole will move down with said lever arm, and because of the engagement of said pawl with the back space wheel will turn said back space wheel in the direction of the arrow in Fig. 4 and from the position illustrated in said figure to that shown in Fig. 5 when the right-hand end of the lever 68 will be brought into contact with the top plate and the lever will be held from further movement in this direction. The back space wheel, it will be recalled, is fixedly connected with the shaft 33, so that during 100 this turning movement the shaft will be turned with the back space wheel, and the pawl 43 will slide over a tooth of the ratchet wheel 39 and engage behind said tooth, thus holding the back spacing wheel and the 105 parts controlled thereby in the positions to which they have been moved. The shaft 33 is connected through the pinion 32 and rack 31 with the carriage and consequently the carriage will be moved in reverse direction, 110 the parts being so proportioned and arranged that at each actuation of the back space key 77 the extent of the backward movement of the carriage amounts to one letter space. When the back space key is released the key lever 75, link 74 and lever 68 will be restored to normal position by means of the spring 78. During the latter 115 part of the return movement of the lever 68 the tail 71 of the back space pawl will re- 120

125
130

engage with the under side of the top plate, and thereafter during the remainder of the returning movement the back space pawl will be swung pivotally outward or away 5 from the back space ratchet wheel so that when the parts reach normal position the back space pawl will be completely disengaged from the back space wheel, as shown in Fig. 2. It will be understood that during 10 the back space turning movements of the back space wheel 40 and the shaft 33, these parts will turn relatively to the escapement wheel 35. As soon as the pressure of the carriage main spring is removed from the 15 escapement wheel during the initial part of each back space movement, said wheel will turn slightly in reverse direction, both because of the friction of the pawl 43 on the ratchet wheel 39 and also because of the 20 pressure of the dog spring 54 on the teeth 37 of said escapement wheel. A very slight reverse movement of said escapement wheel, however, suffices to bring the back stop 55 into operative position, as shown in Fig. 8, 25 thereby preventing further turning of said escapement wheel in reverse direction and holding it motionless during the remainder of the back space turning movement of the other parts.

30 It will be noted that in the construction which has been described above the carriage is separably or detachably connected with its escapement mechanism by means of the rack 31 and pinion 32. One or more springs 35 are commonly employed to maintain these two parts in mesh and in the present instance such a spring is preferably used, being shown in Figs. 2 and 3 and indicated by the numeral 79. The spring 79 as herein shown 40 is a flat spring, one end of it being secured by screws 80 to the carriage rack 31 and the other or free end of it abutting against a lug 81 projecting rearwardly from the rear bar 19 of the carriage. Prior to my present 45 invention, however, in machines employing a separable spring pressed connection between the carriage and its letter space feeding devices it has sometimes happened that the back spacing devices have been operated 50 with so much force that the carriage acquires enough momentum to overcome the tension of the spring connecting it with the letter space feeding devices so that the carriage rack will be forced out of engagement with 55 the feed pinion and will allow the carriage to move two or more letter space distances instead of one in backward direction.

The angle at which the teeth of the rack and pinion engage with each other is conducive to this separation or disengagement as will be clearly understood from an inspection of Figs. 2 and 9. In order to prevent this displacement of the parts and the consequent improper backward spacing movement of the carriage, I have provided means

for locking the carriage feed rack and the feed pinion together or in mesh, so as to maintain them positively engaged during the operation of the back spacing devices. In the present instance I have shown said locking means as normally operative and have provided means for unlocking said locking means when the carriage is to be freed or released from its step-by-step feeding mechanism, as, for example, when the carriage 75 release key is operated or when the tabulating devices are operated. It is to be understood, however, that the desired result, which, broadly stated, is the provision of means for locking the carriage to its step-by-step feeding mechanism at one time and for unlocking said carriage from its step-by-step feeding mechanism at another time so as to enable said carriage to be freed or released at will from said mechanism, may be 80 accomplished in a variety of ways of which the one shown herein and now to be described is an example.

A locking member or latch 82 is pivoted on a shouldered screw 83 which is threaded 90 into the lug or boss 81 projecting from the rear bar of the carriage. As most clearly appears in Figs. 1 and 11 the lock or latch 82 is disposed directly above the carriage feed rack 31. The latch is formed with a locking face 84, which, as shown in Fig. 2, normally co-operates with the top of a pin or abutment 85 fixed to and projecting vertically upward from the top of the feed rack 31. By the construction thus far described it will be seen that the feed rack is prevented from swinging on its pivots 26 and is normally maintained and positively connected to or locked in mesh with the feed pinion 31. Consequently during the letter 100 space feeding movement or during step-by-step back spacing movements of the carriage, the latter will be locked to or positively connected with its letter space feeding or escapement mechanism. In order to 110 unlock the positive connection so as to enable the carriage to be freed or released from its step-by-step feeding mechanism I provide a bar 86 that extends for the greater part of its length parallel with the rack and 115 at the rear thereof. The end portions of said bar, as best shown in Fig. 3, are offset rearwardly and are fixedly connected by headed screws 87 with angular arms 88, said arms being suitably secured as by soldering 120 in a fixed relation with the associate bearing sleeves 25. Each bearing sleeve is provided with a flange 25^a which is arranged between the bearing lug 24 and the forward end of the arm 88 and serves to maintain 125 the arm separated from the inner face of the bearing lug so as to avoid friction thereon. The outer end portion of each bearing sleeve is reduced to receive a release lever 89 which is maintained in fixed relation with 130

the sleeve by a headed screw 90 which takes into a threaded opening in the end of the sleeve and the release lever is clamped between the head of the screw and the shoulder formed by reducing the end of the sleeve so that when said lever is operated by the usual key or finger piece 91 at its forward end the sleeve is caused to turn with it, acting through the arms 88 to lift the bar 86. The bar 86 and the arms 88 to which it is screwed constitute in effect a bail which is pivoted in the bearing lugs 24 at the sides of the carriage. The keys 91 at opposite sides of the carriage are connected in a like manner to the bail and either key may be employed to actuate it.

In the neighborhood of the latch 82 the bar 86 is provided with an upward extension 92, which extension is formed with a horizontal slot 93, said slot receiving a pin or lug 94 projecting rearwardly from the lower end of the latch 82. Below the pin 85 the carriage rack 31 is provided with a rearwardly extending horizontal pin or lug 95 which passes through a perforation or opening 96 in the bar 86. The opening 96 is of considerably greater diameter than the pin 95 so as to allow relative movement between the bar 86 and carriage rack. Normally the bar 86 lies in the position shown in Fig. 2 with the upper edge of the hole or opening 96 resting against the pin 95.

As will be seen from an inspection of Fig. 2 the pin 94 is normally near the right-hand end (considered from the rear) of the slot 93. When either of the release keys 91 is actuated the bar 86 will swing upwardly as has been described, but during the first part of its upward movement will not affect the carriage feed rack 31, because of the lost motion connection between the two provided by the pin 95 and opening 96. In other words, the bar 86 will move upwardly and the top of the opening 96 will move away from the pin 95, which pin together with the carriage feed rack 31 and the pin 85 will remain quiescent until the lower edge of the opening engages with the pin 95, as indicated in Fig. 9. From an inspection of the latter figure and a comparison of it with Fig. 2 it will be seen that during this part of the upward movement of the bar 86 the pin 94 will be moved away from the end of the slot 93 and towards the middle thereof, causing the latch 82 to be swung about its pivot 83 to the left (as viewed in Fig. 9), and so as to disengage the locking face 84 of said latch from the top of the pin 85 with which it co-operates. Further depression of a release key 91 will cause the bar 86 to be swung upward from the position indicated in Fig. 9 to that indicated in Fig. 10, excessive upward movement being checked by the engagement of the top of the pin 85 with the circular rim of the latch

82. During the second part of the movement of the bar 86 the carriage feed rack 31 will be moved with it by reason of the engagement of the lower edge of the opening 96 with the pin 95, and will disengage from the feed pinion 32 so that the carriage will be released from its step-by-step feeding mechanism and may be moved freely by hand in either direction. When the key 91 is released the bar 86 will swing downward and during the first part of its movement the feed rack 31 will move with it to reengage with the feed pinion. After this reengagement the carriage feed rack will be arrested and the bar 86 and the release keys will complete their downward movement until they reach the normal position indicated in Fig. 2.

It will be understood from an inspection of Fig. 3 that during the first part of the upward movement of the bar 86 the sleeves 25 will turn in the bearing lugs 24 and will turn around the pivot pins 26 of the feed rack 31 which pivot pins remain motionless, but after the feed rack has been taken up by the bar 86 the pivot pins 26 will turn with the sleeves 25 during the remainder of the upward movement of the parts. The reverse of this operation takes place during the downward movement of the parts. From the construction as thus far described it will be understood that though the feed rack is normally maintained positively locked to or in mesh with the feed pinion, yet when one of the release keys is operated the locking connection between the feed rack and pinion is automatically unlocked so that the carriage is readily released from its step-by-step feeding mechanism.

When tabulating devices are employed in connection with the typewriting machine it is, of course, necessary to release the carriage from its step-by-step feeding mechanism when the tabulating devices are operated in order to bring about a co-operation between the tabulator stops. When the separable parts of the step-by-step feeding mechanism are normally locked as in the herein described form of my invention it is necessary to effect an unlocking of the locking means for the step-by-step feeding mechanism when the tabulating devices are operated in order that they may be effective. The means for this purpose herein shown and now to be described are illustrated in combination with tabulating devices which are the invention of Jacob Felbel (see his application Sr. No. 270,527, filed July 20th, 1905) and which will be described briefly and only so far as is necessary to an understanding of their operation in connection with the rack locking devices which are part of the subject-matter of the present application.

Referring to Figs. 1 and 2, arms 97 extend horizontally from the rear bar 19 of the car-

riage, one at each side thereof. These arms support a toothed stop bar 98, said stop bar receiving one or more adjustable column stops 99. It will be seen that the curved standards or brackets 23 that support the fixed guide rails 21 are so shaped that the arms 97, stop bar 98 and column stops 99 may move freely from side to side of the machine as the carriage is moved without obstruction. Coöperative with the column stops 99 are a set of denomination stops, said stops being in the form of upright levers 100 having forwardly curved stopping portions 101, said levers being pivoted between their ends at 102 in a supporting frame or bracket 103 suitably secured to the machine at the rear. Coiled springs 104 co-operate with the lower arms of the stop levers 100 to maintain the stopping portions 101 normally out of the path of the column stops. Operative on the end portion of the lower arm of each denomination stop lever 100 is a slide bar 105 mounted to slide in guide ways in a frame 106 which is suitably secured to transverse frame bars 107 and 108. Rising from the guide frame 106 are webs or brackets 109 which are perforated as indicated at 110 to provide bearings for the rock shafts 111. Fixed to each rock shaft is a downwardly extending arm 112 arranged to coöperate with the forward end of one of the slide bars 105. Each rock shaft has fixed to it also a horizontally disposed and forwardly extending tabulating lever 113 which has an upwardly curved portion terminating in a key 114, the series of tabulating keys being disposed at the rear of and above the last bank of keys in the regular keyboard of the machine and the key levers 113 which said tabulating keys operate being guided in a guide plate 115 fixed by screws 116 to the guide frame 106.

It will be understood that when any tabulating key is operated it turns its rock shaft 111, causing the arm 112 fixed thereto to push the associate slide bar 105 rearwardly, said slide bar actuating one of the denomination levers 100 and swinging the lower arm of the latter rearwardly and the upper arm of the latter forwardly about the pivot 102 and bringing the stop portion 101 into the path of the column stops 99. A universal bar 117 operated to actuate the carriage release mechanism is arranged behind the lower arms of the denomination stop levers 100 in position to be actuated by each of said lower arms when it is moved rearwardly as just described. The universal bar 117 is mounted in the supporting frame or bracket 103, said bar having an arm 118 depending from it at each end and each of said arms being pivoted as indicated at 119 in the supporting frame 103. Extending forwardly from the right-hand arm 118 is a horizontal arm 120 provided with a lateral pin 121 which pin co-

operates with the forked lower end of a vertically disposed link 122 operating to raise said link when the universal bar 117 is actuated. The upper end of the link 122 is detachably connected with a lever 123 pivoted at its right-hand end at 124 in a lug 125 depending from the top plate. The left-hand end of the lever 123 (or as viewed from the rear of the machine its right-hand end) has pivotally connected to it at 126 a lifting member 127, said member being bifurcated at its upper end portion, the arms 128 of the bifurcation embracing the bearing bracket 34 and being slidable in guide grooves therein as indicated in Figs. 9 and 10.

As best shown in Figs. 1 and 11 the tops of the arms 128 of the lifting member are directly beneath the lower edge of the release bar 86 and when the tabulator key 114 is operated the lever 123 is swung upward about its pivot, raising the lifting member 127 and causing the arms to lift the bar 86. This bar with its supporting arms constitutes, as previously stated, a bail and when it is raised by the member or bail lifter 127 it operates in the manner previously explained in connection with the operation of the release keys 91. It is to be understood, of course, that during the operation of the release keys the bail lifter 127 remains inoperative. The manner of releasing the latch 82 and lifting the rack by the bar 86 having been explained at length, it is not thought necessary to go into details concerning them at this stage. As has been stated, the first portion of the upward movement of the bar 86 swings the latch 82 to releasing position as shown in Fig. 9 and the further upward movement of the bar 86 carries with it the carriage rack 31, causing the latter to separate from the pinion 32, the latch 82, the feed rack and the releasing bar returning to normal position as previously explained and the bail lifter 127, its actuating lever 123 and link 122 being restored to normal position under the influence of gravity.

In the construction just explained, the lower edge of the lifting bar 86 is on a level with the points of the teeth of the rack 31, and the lifting arms 128, during the first part of their upward movement, carry the lower edge of the bar 86 above the bottoms of the teeth of the rack 31 as shown in Fig. 9. In Fig. 12 I have illustrated a modified construction of rack lifter which necessitates a modification of the bar 86. In the modified construction the arms 128^a at the top of the lifting member are bent forwardly and horizontally to provide lifting portions 128^b, and the lower edge of the lifting bar 86^a normally lies some distance below the teeth of the rack 31. When this construction is employed and any tabulating key is operated the lifting member is raised, causing the rear portions of the lifting shoes 128^b to raise the

bar 86^a until the lower edge of said bar is on the level with the bottoms of the rack teeth. This first portion of the movement operates to release the latch 82. During further upward movement of the lifting shoes 128^b they operate to raise not only the bar 86^a but also the rack 31 until the latter is entirely disconnected from the pinion 32. With this construction it is obvious that when the tabulating keys are operated the pin and slot connection 95—96 is not needed, but of course this connection must be retained for use in connection with the operation of the release key 91.

15 It will be apparent that I have provided a locking means which is normally operative to lock positively the separable connection between the carriage and its step-by-step feeding mechanism but is automatically unlocked when the release keys or tabulator keys are operated; and that when my invention is employed and the back spacing devices are operated the separable connection is positively locked.

20 In order to facilitate the adjustment of the carriage rack relatively to the carriage in assembling the parts, I provide, as shown in Fig. 3, adjusting screws 129 which are supported in the rack arms or devices 28 and 30 pass through openings 130 in the supporting arms 88 of the lifting bar 86. The screws 129 are adjustable transversely of the rack arms 28 and their ends are adapted to abut against the inner faces of the bearing lugs 35 24 of the carriage. Each screw is provided with a locking or check nut 131. The pivot pins 26 are movable in the bearing sleeves 25 in the direction of the axes of said pivot pins and the flanges 27 of the two pivot pins are 40 spaced apart a less distance than are the inner ends of the two sleeves 25. It will be apparent that by turning the screws 129 the pivot pins may be given movement in the direction of their axes and the carriage rack 45 31 which is carried by the arms 28 fixed to said pivot pins will be moved longitudinally relatively to the carriage. This provides a ready and simple method of effecting a relative adjustment between the parts. The 50 opening 130 in the arms 88 permit said arms to turn on their pivots without affecting the screws 129 or the arms 28 in which said screws are supported, and likewise permit swinging movement of the arms 28 without 55 affecting the arms 88.

Various changes may be effected within the scope of my invention and parts of it may be used without other parts.

What I claim as new and desire to secure 60 by Letters Patent, is:—

1. In a typewriting machine, the combination of a carriage; a shaft normally operatively connected thereto; a toothed back space wheel mounted on said shaft; a back 65 space pawl coöperative with said back space

wheel; a hand actuated lever to which said pawl is pivoted; a fixed stop with which said lever normally coöperates; a fixed stop for said back space pawl; and a spring normally maintaining said pawl against its stop 70 and separated from said back space wheel.

2. In a typewriting machine, the combination of a carriage; a shaft normally operatively connected thereto; a toothed back space wheel mounted on said shaft; a back 75 space pawl coöperative with said back space wheel; a lever of the first order fulcrumed on the machine frame, said pawl being pivoted to one arm of said lever; a key at the keyboard operatively connected with the 80 other arm of said lever; a fixed stop with which said lever normally coöperates; a fixed stop for said back space pawl; and a spring normally maintaining said pawl against its stop and separated from said 85 back space wheel.

3. In a typewriting machine, the combination of a carriage; step-by-step feeding mechanism therefor; means for at will releasing the carriage from its step-by-step 90 feeding mechanism at any desired point between the beginning and end of the travel of said carriage; and means for locking said step-by-step feeding mechanism in coöperative relation with said carriage. 95

4. In a typewriting machine, the combination of a carriage; step-by-step feeding mechanism therefor; means for at will releasing the carriage from its step-by-step feeding mechanism at any desired point between the beginning and end of the travel of said carriage; and means for locking said step-by-step feeding mechanism in coöperative relation with said carriage, said last named means comprising a locking member 100 pivoted on the carriage.

5. In a typewriting machine, the combination of a carriage; step-by-step feeding mechanism therefor; means for at will releasing the carriage from its step-by-step 110 feeding mechanism at any desired point between the beginning and end of the travel of said carriage; and means normally maintaining a locked engagement between said step-by-step feeding mechanism and said carriage. 115

6. In a typewriting machine, the combination of a carriage; carriage feeding devices normally in coöperative relation; means for at will disconnecting certain of said devices 120 to release the carriage; means for automatically locking said disconnectible devices in operative relation; and means for releasing said locking means at any desired point between the beginning and end of the travel of 125 said carriage.

7. In a typewriting machine, the combination of a carriage; carriage feeding devices normally in coöperative relation; means for at will disconnecting certain of said devices 130

to release the carriage; means for automatically locking said disconnectible devices in operative relation; and means controlled by an actuation of said disconnecting means for 5 automatically releasing said locking means at any desired point between the beginning and end of the travel of said carriage.

8. In a typewriting machine, the combination of a carriage; carriage feeding devices including a rack and pinion; means for at will disconnecting said rack and pinion at any desired point between the beginning and end of the travel of said carriage; and means for locking said rack and pinion in mesh.

15 9. In a typewriting machine, the combination of a carriage; carriage feeding devices including a rack and pinion; means for at will disconnecting said rack and pinion at any desired point between the beginning and 20 end of the travel of said carriage; means for automatically locking said rack and pinion in mesh; and means for automatically releasing the locking means when said disconnecting means are actuated.

25 10. In a typewriting machine, the combination of a power-driven carriage; a feed rack connected thereto; step-by-step feeding devices for said carriage including a feed pinion with which said rack normally 30 meshes; means including a release key on the carriage for separating said rack and pinion to release said carriage at any desired point between the beginning and end of the travel of said carriage; and locking means 35 for preventing the separation of said rack and pinion.

11. In a typewriting machine, the combination of a power-driven carriage; a feed rack connected thereto; step-by-step feeding 40 devices for said carriage including a feed pinion with which said rack normally meshes; means for at will separating said rack and pinion to release the carriage at any desired point between the beginning and 45 end of the travel of said carriage; and means normally locking said rack and pinion in engagement.

12. In a typewriting machine, the combination of a power-driven carriage; a feed 50 rack connected thereto; step-by-step feeding devices for said carriage including a feed pinion with which said rack normally meshes; means normally locking said rack and pinion in engagement; means for at will 55 separating said rack and pinion to release the carriage at any desired point between the beginning and end of the travel of said carriage; and automatic means for rendering 60 said locking means inoperative during the carriage releasing operation.

13. In a typewriting machine, the combination of a power-driven carriage; a feed rack pivotally connected thereto; step-by-step feeding devices for said carriage including a feed pinion with which said rack

normally meshes; means for swinging said rack on its pivots to release said carriage from its step-by-step feeding devices; a latch pivotally connected with said carriage and normally operative on said rack to maintain it locked in mesh with said feed pinion; and means for automatically swinging said latch to inoperative position when the carriage is released.

70 14. In a typewriting machine, the combination of a power-driven carriage; a feed rack pivotally connected thereto; step-by-step feeding devices for said carriage including a feed pinion with which said rack normally meshes; means for swinging said 75 rack on its pivots to release said carriage from its step-by-step feeding devices; a latch pivotally connected with said carriage and normally operative on said rack to maintain it locked in mesh with said feed 80 pinion; a member pivotally connected with the carriage and operative to unlock said latch and to swing said rack to releasing position; and a key for actuating said member.

85 15. In a typewriting machine, the combination of a power-driven carriage; a feed rack pivotally connected thereto; step-by-step feeding devices for said carriage including a feed pinion with which said rack normally meshes; means for swinging said 90 rack on its pivots to release said carriage from its step-by-step feeding devices; a latch pivotally connected with said carriage and normally operative on said rack to maintain it locked to said feed pinion; and a key-actuated bail pivoted on said carriage and 95 operative to unlock said latch and swing said rack to releasing position.

100 16. In a typewriting machine, the combination of a power-driven carriage; a feed rack connected thereto; step-by-step feeding 105 devices for said carriage including a feed pinion with which said rack normally meshes; means normally locking said rack and pinion in engagement; key actuated tabulating devices, said tabulating devices 110 operating to separate said rack and pinion to release the carriage; and automatic means for rendering said locking means inoperative when said tabulating devices are actuated.

115 17. In a typewriting machine, the combination of a carriage; feed mechanism therefor including separable members which when separated afford a free run of the carriage; locking means for maintaining said separable members in co-operative relation; and tabulating mechanism including carriage releasing means operable on said separable members and co-operative with said locking means to automatically release the same.

120 18. In a typewriting machine, the combination of a carriage; feed mechanism therefor including separable members which when separated afford a free run of the carriage; automatically operating locking means

- for maintaining said separable members in coöperative relation; and key actuated tabulating mechanism including carriage releasing means operable on said separable members to release the carriage when the tabulating mechanism is actuated and coöperative with said locking means to automatically release the same.
19. In a typewriting machine, the combination of a power-driven carriage; a feed rack pivotally connected thereto; step-by-step feeding devices for said carriage including a feed pinion with which said rack normally meshes; means for swinging said rack on its pivots to release said carriage from its step-by-step feeding devices; a latch pivotally connected with said carriage and operative to unlock said latch and to swing said rack to releasing position; key actuated tabulating devices; and connections between said tabulating devices and said member, whereby the latter is operated when the tabulating devices are actuated.
20. In a typewriting machine, the combination of a power-driven carriage; a feed rack pivotally connected thereto; step-by-step feeding devices for said carriage including a feed pinion with which said rack normally meshes; means for swinging said rack on its pivots to release said carriage from its step-by-step feeding devices; a latch pivotally connected with said carriage and normally operative on said rack to maintain it locked in mesh with said feed pinion; a releasing bail pivoted to said carriage and operative to unlock said latch and to swing said rack to releasing position; a bail lifter; a supporting lever on the frame of the machine to which said bail lifter is pivoted; a column stop adjustable on said carriage; a plurality of coöperating key actuated tabulating stops mounted on the frame of the machine; a universal releasing bar operative by each of said coöperating tabulating stops; and a link operatively connecting said universal releasing bar with said supporting lever.
21. In a typewriting machine, the combination of a power-driven carriage; a feed rack pivotally connected thereto; step-by-step feeding devices for said carriage including a feed pinion with which said rack normally meshes; means for swinging said rack on its pivots to release said carriage from its step-by-step feeding devices; a latch pivotally connected with said carriage and normally operative on said rack to maintain it locked in mesh with said feed pinion; a release bail pivoted to said carriage and operative to unlock said latch and to swing said rack to releasing position; a carriage release key operative on said bail; a bail lifter pivoted on the frame of the machine; key actuated tabulating devices; and connections between said tabulating devices and said bail lifter.
22. In a typewriting machine, the combination of a carriage; carriage feeding devices including members separable at any desired point between the beginning and the end of the carriage travel to afford free travel of the carriage; back spacing mechanism; and locking means for said separable members which locking means prevent the back spacing mechanism when operated from separating said members.
23. In a typewriting machine, the combination of a power-driven carriage; a feed rack pivotally connected thereto; step-by-step feeding devices for said carriage including a feed pinion with which said rack normally meshes; means for separating said rack and pinion at any desired point between the beginning and the end of the carriage travel; back spacing devices operative to move the carriage in reverse direction a letter space distance at a time; and locking means for said rack and pinion, which locking means prevent the back spacing devices when operated from separating said rack and pinion.
24. In a typewriting machine, the combination of a power-driven carriage; a feed rack pivotally connected thereto; step-by-step feeding devices for said carriage including a feed pinion with which said rack normally meshes; means for separating said rack and pinion at any desired point between the beginning and the end of the carriage travel; a toothed back spacing wheel mounted on the shaft which carries said pinion; actuating means for operating said back spacing wheel; and locking means which prevent the back spacing wheel when operated from separating said rack and pinion.
25. In a typewriting machine, the combination of a power-driven carriage; a feed rack pivotally connected thereto; step-by-step feeding devices for said carriage including a feed pinion with which said rack normally meshes; means for swinging said rack on its pivots to release said carriage; a back space wheel fixed to the shaft which carries said feed pinion; a back space pawl operative on said back space wheel; a lever to which said pawl is pivoted; key actuated means for operating said lever; and means for preventing said rack and pinion from separating when said key actuated means is operated.
26. In a typewriting machine, the combination of a power-driven carriage; a feed rack pivotally connected thereto; step-by-step feeding devices for said carriage including a feed pinion with which said rack normally meshes; means for swinging said rack on its pivots to release said carriage; a back

- space wheel fixed to the shaft which carries said feed pinion; a back space pawl coöperative with said back space wheel; a hand-actuated lever to which said pawl is pivoted; 5 a fixed stop with which said lever normally coöperates; a fixed stop for said back space pawl; a spring normally maintaining said pawl against its stop and separated from said back space wheel; and means for preventing said rack and pinion from separating when said lever is actuated.
27. In a typewriting machine, the combination of a power-driven carriage; a feed rack pivotally connected thereto; step-by-step feeding devices for said carriage including a feed pinion with which said rack normally meshes; means for swinging said rack on its pivots to release said carriage; a latch pivotally connected to said carriage and normally operative on said rack to maintain it locked in mesh with said feed pinion; means for automatically swinging said latch to inoperative position when the carriage is released; a toothed back space wheel fixed 20 to the shaft on which said feed pinion is mounted; a back space pawl coöperative with said back space wheel; and hand-actuated means for operating said pawl.
28. In a typewriting machine, the combination of a power-driven carriage; a feed rack pivotally connected thereto; step-by-step feeding devices for said carriage including a feed pinion with which said rack normally meshes; means for swinging said rack 30 on its pivots to release said carriage; a latch pivotally connected with said carriage and normally operative on said rack to maintain it locked in mesh with said feed pinion; means for automatically swinging said latch to inoperative position when the carriage is released; a toothed back space wheel fixed to the shaft on which said feed pinion is mounted; a back space pawl coöperative 35 with said back space wheel; a lever of the first order pivoted to the machine frame, said pawl being pivoted to one arm of said lever; a key at the keyboard operatively connected with the other arm of said lever; a fixed stop with which said lever normally 40 coöperates; a fixed stop for said back space pawl; and a spring normally maintaining said pawl against its stop and separated from said back space wheel.
29. In a typewriting machine, the combination of a power-driven carriage; a feed rack pivotally connected thereto; step-by-step feeding devices for said carriage including a feed pinion with which said rack normally meshes; an escapement wheel 45 loosely mounted on the shaft which carries said feed pinion; escapement dogs coöperative with said escapement wheel; back spacing devices operative to move the carriage in reverse direction a letter space distance at a

time; means for preventing the separation 65 of said rack from the pinion when said back spacing devices are operated; and a back stop for preventing undue turning of said escapement wheel in reverse direction when said back spacing devices are operated. 70

30. In a typewriting machine, the combination of a power-driven carriage; a feed rack pivoted thereto; step-by-step feeding devices for said carriage including a feed pinion normally meshing with said rack, 75 an escapement wheel loosely mounted on the shaft which carries said pinion and escapement dogs coöperative with said escapement wheel; means for swinging said rack on its pivots to release said carriage; a latch pivotally connected with said carriage and normally operative to maintain said rack locked to said feed pinion; means for automatically swinging said latch to inoperative position when the carriage is released; a back space 80 wheel fixed to the shaft which carries said feed pinion; hand-actuated means for operatively turning said back space wheel; and a back stop carried by the normally engaged one of said escapement dogs and operative to 85 prevent undue reverse movement of said escapement wheel when said back space wheel is operatively turned.

31. In a typewriting machine, the combination of a carriage; a feed rack; pivoted 95 key actuated devices connecting the rack to the carriage; and adjusting screws carried by said key actuated devices and coöperating with the carriage for regulating the lengthwise position of the rack on the carriage. 100

32. In a typewriting machine, the combination of a carriage; a feed rack; arms pivoted to said carriage and carrying said feed rack, said arms being capable of bodily movement; and devices mounted on said arms and 105 operative to communicate bodily movement to them, whereby said feed rack is longitudinally adjusted relatively to the carriage.

33. In a typewriting machine, the combination of a carriage; arms each provided at 110 one end with a pivot capable of movement on said carriage in the direction of the axis of said pivot; a feed rack supported at the other ends of said arms; and adjustable screws carried by said arms and coöperative 115 with said carriage to communicate movement to the pivots of said arms in the direction of the axes of said pivots; whereby said feed rack is moved relatively to said carriage. 120

Signed at Syracuse, in the county of Onondaga, and State of New York, this 4th day of May A. D. 1906.
